UNITED STATES PATENT OFFICE

148,046

DESIGN FOR A SCOOTER OR SIMILAR ARTICLE

Frank Brogan, Cincinnati, Ohio

Application March 11, 1946, Serial No. 127,364

Term of patent 14 years

(Cl. D90—8)

To all whom it may concern:

Be it known that I, Frank Brogan, a citizen of the United States of America, residing at Cincinnati, in the county of Hamilton, State of Ohio, have invented a new, original, and ornamental Design for a Scooter or Similar Article, of which the following is a specification, reference being had to the accompanying drawing, forming part thereof.

Fig. 1 is a perspective view of the scooter or similar article, showing my new design.

Fig. 2 is a side elevational view of the same on a slightly reduced scale.

Fig. 3 is a top plan view thereof.

The characteristic features of my design reside in the portions shown by means of full lines in the drawing.

I claim:

The ornamental design for a scooter or similar article, as shown and described.

FRANK BROGAN.
